(57) **CLAIM**

The ornamental design for a climbing frame, as shown and described.

DESCRIPTION

FIG. 1 is a front, right, and top perspective view of a first embodiment of a climbing frame showing my design. FIG. 2 is a front, right, and bottom perspective view of FIG. 1.

FIG. 3 is a front elevation view of FIG. 1.

FIG. 4 is a rear elevation view of FIG. 1.

FIG. 5 is a left side elevation view of FIG. 1.

FIG. 6 is a right side elevation view of FIG. 1.

FIG. 7 is a top plan view of FIG. 1.

FIG. 8 is a bottom plan view of FIG. 1.

FIG. 9 is an enlarged view thereof, taken from encircled portion "9" in FIG. 1.

FIG. 10 is an enlarged view thereof, taken from encircled portion "10" in FIG. 1.

FIG. 11 is an enlarged view thereof, taken from encircled portion "11" in FIG. 2.

FIG. 12 is a front, right, and top perspective view of a second embodiment of a climbing frame showing my design.

FIG. 13 is a front, right, and bottom perspective view of FIG. 12.

FIG. 14 is a front elevation view of FIG. 12.

FIG. 15 is a rear elevation view of FIG. 12.

FIG. 16 is a left side elevation view of FIG. 12.

FIG. 17 is a right side elevation view of FIG. 12.

FIG. 18 is a top plan view of FIG. 12.

FIG. 19 is a bottom plan view of FIG. 12.

FIG. 20 is an enlarged view thereof, taken from encircled portion "20" in FIG. 12.

FIG. 21 is an enlarged view thereof, taken from encircled portion "21" in FIG. 12; and,

FIG. 22 is an enlarged view thereof, taken from encircled portion "22" in FIG. 13.

The even-dash broken lines shown in the drawings illustrate portions of the climbing frame that form no part of the

(Continued)

claimed design. The dot-dash broken lines in FIGS. 1-2, 9-13, and 20-22 depict the bounds of the enlarged views and form no part of the claimed design.
